UNITED STATES PATENT OFFICE.

GEORGE WILLIAM PARK, OF DENVER, COLORADO.

ERASER.

No. 845,889.

Specification of Letters Patent.

Patented March 5, 1907.

Application filed May 11, 1905. Serial No. 259,914.

To all whom it may concern:

Be it known that I, GEORGE WILLIAM PARK, a citizen of the United States, and a resident of Denver, in the city and county of Denver and State of Colorado, have invented a new and Improved Eraser, of which the following is a full, clear, and exact description.

This invention relates to erasers; and it consists, substantially, in the details of construction and combinations of parts herein-after more particularly described, and pointed out in the claims.

One of the principal objects of the invention is to provide an eraser combined with or forming a part of the tubular member ordinarily employed with fountain-pens for protecting the pen or writing-point thereof.

A further object is to provide an eraser (thus associated with a fountain-pen) which is simple in construction and comparatively inexpensive to manufacture, besides being thoroughly effective and reliable for its purposes and possessing the capacity for long and repeated service.

The above and additional objects are attained by means substantially such as are illustrated in the accompanying drawings, in which similar characters of reference indicate corresponding parts in all the figures.

Figure 1 is a side view of a fountain-pen provided with the ordinary tubular member for protecting the pen or writing-point thereof. Fig. 2 is a part-sectional view of an eraser embodying my improvements and showing the same as combined with or forming a part of the ordinary tubular protecting member for the pen or writing-point of a fountain-pen, and Fig. 3 is a view in perspective of the eraser detached.

Before proceeding with a more detailed description it may be stated that in the forms of my improvements herein shown I employ an ordinary fountain-pen having a tubular protector for the writing-point thereof of special construction, associated or combined with which is a detachable eraser of special construction.

Reference being had to the accompanying drawings by the designating characters marked thereon, 1 represents an ordinary fountain-pen provided at 2 with a member for protecting the writing-point 2^a thereof when the pen is carried in the pocket, said member in the present instance being pro-

vided with a detachable cap or closure 3 therefor.

As shown in Fig. 2, the cap or closure 3 is internally threaded at the open end thereof to screw upon a corresponding threaded projection 4, formed integral with the upper end of the said member 2 and reduced in external diameter, as shown, said projection 4 being also internally threaded at 5 to engage a corresponding thread 6, formed externally with a plug 7, which is provided with recesses in its ends, as shown at 8, and has inserted in one recess a block 9 of rubber, either for pencil or ink erasures, the shank of a knife-eraser 10 being secured in the recess 7c in the other end of the said plug, the knife-eraser extending diametrically across the same with a knife-eraser 10 and tapered to a point, as shown, and formed on each side thereof at 11 with an erasing or cutting edge. 75 It will thus be seen that when my improved eraser is not in use the cap or closure 3 may be applied to the member 2 flush therewith, so that not only will the pen-point 2^a be protected when the same is inserted within the member 2, but the eraser will also be protected from injury and prevented from being lost or misplaced, as is apparent.

From the foregoing it will be seen that I have provided a very simple device which 85 may be conveniently associated with a fountain-pen and carried in the pocket with the latter to be always available for use when required, and it is thought the advantages of my improvements will be apparent. 90

In making use of the invention it is simply necessary to unscrew or slip off the cap or closure 3 to enable simply the rubber eraser 9 to be used in the ordinary way; but whenever it is desired to use the knife-eraser 8 the 95 plug or cap 6 is unscrewed from its connection with the threaded projection 4 of the member 2, whereupon either edge of the said knife-eraser may be employed in the ordinary way by simply grasping the plug 6 between 100 the fingers and thumb of the hand. After use the device may be again inserted within the member 2, as before, and the cap or closure 3 applied.

Whenever the plug 9 has become worn 105 away, it may be readily replaced, of course, and so, too, may the knife-eraser of either form herein shown be replaced by another when it has become worn or otherwise unfit for use.

Having thus described my invention, I claim as new and desire to secure by Letters Patent—

1. A protecting-cover for a fountain-pen open at both ends and having one end externally and internally screw-threaded, said cover having an internally-screw-threaded cap screwing on the said cover, an externally-screw-threaded plug screwing into the cover and having a recess in each end, said plug being of even diameter throughout and having its screw-thread extending throughout its length, a block of rubber in one recess of the plug, and a blade tapering to a point and having a shank fitting in the other recess of said plug, the base of the blade being approximately of a width equal to the diameter of the plug.

2. A protecting-cover for a fountain-pen open at both ends and having one end internally screw-threaded, an externally-screw-threaded plug screwing into the cover and having a recess in each end, said plug being of even diameter throughout and having its

screw-thread extending the length thereof, a block of rubber in one recess of the plug, and a blade tapering to a point and having a shank fitting in the other recess of the said plug, the base of the blade being of a width approximately equal to the diameter of the plug.

3. As a new article of manufacture a protecting-cover for a fountain-pen, comprising an open-ended shell having one end reduced and internally screw-threaded at said reduced end, a removable cap fitting on the reduced end of the shell, and an exteriorly-screw-threaded plug screwing into the shell and provided with a block of rubber in one end and a blade in the other end.

In testimony whereof I have signed my name to this specification in the presence of two subscribing witnesses.

GEORGE WILLIAM PARK.
